SPACE DISCHARGE DEVICE

Hans Erich Hollmann, Berlin-Lichterfelde, Germany, assignor to Radio Patents Corp., New York, N. Y., a corporation of New York

Application April 14, 1937, Serial No. 136,748
In Germany June 23, 1936

10 Claims. (Cl. 250—27)

The present invention relates to electric space discharge devices for use in the amplification, modulation and rectification of electric currents or potentials, more particularly to devices of the type wherein a concentrated electron discharge beam is impinged upon a target or output electrode and deflected in accordance with a controlling signal or magnitude so as to strike the target electrode with varying cross-sections to cause a corresponding variation or modulation of the current in an associate output circuit. Devices of this character are known as deflector or beam discharge tubes as distinct from the ordinary type of electron tube wherein the intensity or density of an electron discharge current is controlled by varying the so-called "space charge" within the tube by means of a grid or equivalent control element.

In a known type of deflector discharge tube of the above character, two output or target anodes are arranged adjacent to each other and connected to a common output circuit in push-pull arrangement. In the normal position the electron beam strikes both targets equally resulting in the same current flow in the associate output circuits. If the beam is deflected in either direction in accordance with a controlling signal or magnitude, more current will be collected by one of the target anodes than by the other target anode in such a manner that the current differential in the associate output circuits may serve to operate a translating device or to produce a control potential for a subsequent amplifying stage.

A disadvantage of discharge devices of the aforementioned character is the fact that secondary electron emission may take place from the output or target anode when struck by the primary electrons of the impinging electron beam. Since the secondary electrons emitted from a target anode cannot move against the field accelerating the electron beam, they will accumulate and form a space charge or electron cloud in front of the target anode. This disadvantage is of a specially serious nature if a high potential difference exists between the target anodes as is the case in a push-pull arrangement of the type described. In the latter case, the secondary electrons will pass from the less negative target anode to the more positive target anode thereby forming an electronic resistive path therebetween which greatly impairs the sensitivity and effectiveness of the electron beam control.

In order to eliminate the above defect it has been suggested to provide a suppressor grid in front of the target anode in the path of the elec-

tron beam. This suppressor grid serves to collect the secondary electrons emitted from the target anode in a manner similar to the suppressor grids provided in the ordinary pentode amplifying tubes known in the art. While it is possible by this expedient to secure an almost complete elimination of the effect of secondary emission from the target anode, a new difficulty arises by reason of the fact that the primary electrons of the discharge beam become decelerated by the action of the opposing field between the suppressor grid and target anode, resulting in a substantial impairment of the concentration of the electron beam. As a result, the impinging cross-sectional area of the electron beam upon the anode becomes more diffused causing a substantial decrease of the sensitivity of control which latter as is understood depends directly on the size and sharpness of the impinging cross-sectional area of the beam.

An object of the present invention is to remove the above difficulty and to utilize the secondary electron emission for additional amplification of the output current.

Another object of the invention is to increase the sensitivity and efficiency of a discharge device of the above character using a concentrated electron beam deflected in accordance with a controlling signal or magnitude.

Another object is to provide a composite amplifier and electron beam discharge device characterized both by increased efficiency and sensitivity as well as fidelity of the deflection by a controlling signal or magnitude.

A further object of the invention is the provision of a composite direct coupled amplifier and cathode ray device adapted for recording or translating variable magnitudes and characterized by increased fidelity of the record or output current obtained substantially without dependence on the frequency or rate of change of the signal or magnitude being recorded or translated.

The above and further objects and aspects of the invention will become more apparent from the following detailed description taken with reference to the accompanying drawing forming a part of this specification and wherein

Figure 1 illustrates diagrammatically one form of a discharge device constructed according to the invention.

Figure 2 shows a modification of a discharge device of the type according to Figure 1.

Figure 3 is a partial view of a discharge device according to the preceding figures illustrating a further modification of the invention, and

Figure 4 is a further partial view illustrating a composite discharge amplifier and cathode ray device constructed in accordance with the invention.

5 Like reference numerals identify like parts in the different views of the drawing.

According to the improvements of the present invention, the target or collecting electrodes in a deflector tube of the general type described 10 above is of foraminous construction such as in the form of a finely meshed wire net or grid referred to as a target grid for the purpose of this specification. The latter preferably consists of a material having high secondary electron emission 15 by the use of a suitable metal or metal alloy having a high work function or conditioned by special treatment, such as by oxidation or the like, well known in the art. The secondary electrons released due to impact of the electron beam 20 are removed or attracted in the direction of the beam by a further anode or positive electrode disposed behind the target grid and maintained at a positive potential relative to the latter. The electric field produced by this anode extends 25 through the target grid in such a manner that not only secondary electrons released from within the meshes of the grid, but also those released from the front side of the grid are removed and attracted towards the anode. From 30 this it is seen that a decelerating or braking field opposing the main electron beam is avoided whereby the latter may reach the target grids without disturbance and impairment.

Referring more particularly to Figure 1 of the 35 drawing, the same represents a discharge tube illustrating the basic principle of the invention. There is shown at 10 a vessel or envelope including a cathode 11 which may be a thermionic cathode of either the direct or indirectly heated 40 type maintained at a suitable temperature for electron emission by means of a heating source to be connected to terminals 11'. The electrons emitted by the cathode are concentrated or focused into a sharp beam by the aid of a suitable 45 focusing or electron lens system consisting in the example illustrated of a pair of annular acceleration electrodes 12 and 13 maintained at positive potentials relative to the cathode. As is understood, the potential of the electrode 13 is 50 higher than that of the electrode 12. The design of the elements and operating characteristics are furthermore chosen in such a manner that a sharp image of the cathode is formed in a plane containing a pair of grid shaped target anodes 16 and 17 maintained at a suitable positive accelerating potential. The electron beam is deflected in accordance with a controlling signal or magnitude by the aid of any of the well known deflecting 55 means such as a pair of electrostatic deflecting 60 plates 14 and 15 connected to the terminals of a control circuit supplying the current or potential variation to be translated.

As is understood, any other type of deflecting 65 arrangement may be provided such as a pair of magnetic field coils well known in the art of cathode ray tubes. If the deflecting force, that is in the example shown, the controlling electric field, is zero, the axis of the cathode ray will be 70 symmetrical to both the target grids 16 and 17. If the beam is deflected from its zero position towards either the left or the right, it will impinge upon one of the grids 16 or 17 with a greater portion of its cross-sectional area than upon the 75 other grid. In the extreme deflection the entire

beam current will be impinged upon either of the target grids.

According to the present invention there are further provided a pair of solid collecting anodes or suppressor electrodes 18 and 19 disposed behind the target grids 16 and 17, respectively, and serving to attract the secondary electrons emitted from the latter by impact of the electron beam. The suppressor anodes 18 and 19 are maintained at a higher positive potential relative to the target 10 grids 16 and 17, to produce an accelerating field therebetween in such a manner that substantially all the secondary electrons and if desirable the primary electrons passing through the meshes of the target grids 16 and 17 will be attracted towards the anodes without reacting upon or influencing the primary discharge beam prior to its reaching the target grids 16 and 17. 15

In accordance with a further improvement of the invention, the collecting or suppressor anodes 20 18 and 19 serve not only for suppressing the effect of secondary electron emission, but are further utilized for amplifying or multiplying the primary electron current. For the latter purpose the anodes 18 and 19 serve as output electrodes and are 25 connected to the high tension source indicated by the + sign in series with load impedances 20 and 21 while the grids 16 and 17 are constructed of a suitable material or treated to produce high 30 secondary electron emission and are biased by fixed potentials. An output or utilization circuit may be coupled with either or both of the load impedances 20 and 21 in a manner well understood. Since the number of secondary electrons substantially exceeds the number of primary electrons, provided the target grids consist of a suitable 35 material or conditioned to have a high secondary emission or work function, a considerable amplification or multiplication of the primary electron current is obtained substantially free 40 from distortion due to the absence of coupling impedances depending on the frequency or rate of change of the deflecting potentials or currents. As is understood, the output circuit may be connected directly to the target grids 16 and 17 in 45 case no further amplification by secondary emission is required in which case the load impedances 20 and 21 are connected to the grids 16 and 17 and the suppressor anodes 18 and 19 are maintained at a fixed potential. 50

In order to prevent mutual reaction between the discharge paths enclosed by the target grids and the associate output or suppressor anodes due to stray electrons or other coupling effects, there is provided a screen 22 which may be 55 grounded or biased to a potential equal to that of the target grids 16 and 17. Since the latter are at equal positive potential and do not carry alternating currents—the control effect by the target grids is due exclusively to the change in the distribution of the current—the two grids may be directly jointed or constructed in the form of a single electrode. In the latter case, as is understood the output anodes 18 and 19 may remain 60 unchanged. 65

The electric isolation of the two discharge paths for the secondary electrons may be further improved by arranging the target grids 16 and 17 at an angle with the axis of the electron beam such as shown in Figure 2. If both grids are 70 joined as described above, an angular target electrode is obtained whose bisecting plane includes the axis of the electron beam when the latter is in its zero or resting position. There is further shown in Figure 2 an arrangement for further 75

multiplication comprising a plurality of additional secondary emission grids 23, 24 and 26, 27 disposed intermediate the target electrodes 16 and 17 and the collecting or output anodes 18 and 19, respectively. For each of these grids the preceding grid acts as a secondary emission source whereby the number of impinging electrons is multiplied by secondary emission. To obtain this effect the potential of the grids should increase 10 in succession such as by the connection of the grids to successive taps of a suitable biasing source such as a potentiometer or battery shown at 28. By a cascade multiplication of this type considerable final output currents and an extremely high 15 amplification or gain is obtained from a comparatively weak initial electron emission which latter is desirable in the interest of the concentration or electron optical focusing of the electrons into a sharp beam. There is further shown in Figure 20 a resonant output circuit comprising an induction coil 30 shunted by a condenser 31 connected to the output anodes 18 and 19. The coil 30 has a center tap connected to the positive pole of the source 29 to provide the necessary high tension or 25 anode potential. A tube of this type may be used for the amplification of high frequency currents in a variety of circuit connections known in circuits using the ordinary type of electron discharge tubes. Thus, there may be provided a feedback 30 or regenerative circuit such as is shown in Figure 2 wherein portions of the potential drop developed across the inductance 30 are fed back to the input or deflecting plates 14 and 15 for either increasing (regeneration) or decreasing (degeneration) 35 the amplification or for maintaining sustained oscillations to be utilized in an associate output circuit coupled with the inductance 30.

As is obvious, the new deflector discharge tube according to the invention has many uses, especially where distortionless amplification is required independent of the frequency or rate of change of an input signal or magnitude. In a tube constructed according to the invention, the frequency range practically extends from zero, that is pure direct current amplification up to 45 the highest practical frequencies due to the fact that no coupling impedances dependent on frequency or causing electric inertia effect are required, with the exception of the inherent inertia 50 effect of the electron movement and the inertia of the secondary electron emission.

As is understood, the discharge tube as described may comprise a single target grid and anode only in place of the differential or push-pull construction described hereinabove. In the latter case, one of the target grids and associated anode are omitted and replaced by a suitably shaped collecting electrode or screen. As is understood, however, the efficiency and effectiveness of such a tube is inferior to the push-pull construction described.

If the entire primary current is impinged upon the target grids 16 or 17 considerable anode currents are set up due to the amplification by secondary emission. The sum of these currents should remain constant throughout the operation to insure optimum sensitivity and fidelity. The output currents produce voltage drops across the load impedances 20 and 21 dependent on the 70 current distribution whereby the anode supply voltage is decreased by the amount of these voltage drops. Thus, in order to remain within the saturation region and to maintain optimum operating conditions for secondary emission, it 75 is necessary to choose a sufficiently high anode

potential or to limit the load impedances 20 and 21. In the latter case, the amplifying action of the tube may not be utilized to the fullest extent possible.

In order to overcome this disadvantage, there 5 is provided according to Figure 3, an additional target electrode 32 interposed between the main target grids 16 and 17 which serves to collect the central portion of the primary electron beam having a limited and well defined focusing area. 10 The operating conditions are chosen in such a manner that the two target grids are struck only by the marginal cross-sectional zones of the electron beam. Thus, for instance, if the entire focusing area has a width of 3 mm, the auxiliary 15 target 32 may have a width of 2 mm, leaving 1 mm. for both marginal zones; that is $\frac{1}{2}$ mm. for each side. From this it is seen that in a tube of this type, the full control or maximum sweep can be obtained by a deflection of $\frac{1}{2}$ mm. while in an 20 ordinary construction without the auxiliary target 32, a 3 mm. deflection would be required for the same control swing.

In order to prevent the primary electrons impinged upon the auxiliary target 32 from producing a secondary space charge, the auxiliary target 32 is constructed in the form of a grid or wire net so that secondary electrons emitted from it may be attracted by a further anode or suppressor electrode 33 similar to the anodes 18 and 19. To prevent mutual reaction between the discharge paths by stray electrons or the like, a pair 30 of screens 34 and 35 are provided which may be connected to ground or biased to a positive potential equal to the potential of the target grids 35 18, 17 and 32.

The primary electrons attracted towards the anode 33 and the secondary electrons emitted by the auxiliary target 32 are normally lost for the amplification process. However, since the intensity of these electrons remains constant as long as the controlling current or potential of the tube does not become excessive, they may be utilized in accordance with a further improvement of the invention to serve as a source for 45 an electron current in an associate amplifier or cathode ray section combined with the first amplifier section of the tube.

A composite tube construction of this type is illustrated in Figure 4. In the latter, the arrangement of the outer target grids 16 and 17 and the central discharge path between the auxiliary target and suppressor 33 is substantially similar as shown in Figure 3 with the exception that the target grids 16 and 17 and associated output 55 anodes 18 and 19 are arranged at an angle to the axis of the electron beam and that further multiplying secondary emission grids are provided in a manner substantially similar as shown in Figure 2.

Figure 4 differs from Figure 3 by the fact that the auxiliary or suppressor anode for the control portion of the electron beam is constructed in the form of a finely meshed wire net or grid capable of or conditioned to have high secondary emission similar as the remaining multiplying grids in the tube. This suction anode shown at 36 serves as a cathode for producing an electron beam in the adjacent section of the tube which in the example shown is a cathode ray oscilloscope but 70 which may be a similar deflector type amplifier as the first section as is understood. For this purpose, the electrons accumulating in the vicinity of the anode 36 are collected and concentrated by means of a focusing system comprising a pair 75

of suitably biased annular electrodes 40 and 41 in such a manner as to produce a sharply focused reduced electron image upon a target or fluorescent screen 42 as shown in the example illustrated. The electrode 36 may serve as a large surface cathode for the cathode ray in which case the size and shape of the luminous spot will depend on the electron optical focusing characteristics, or alternatively a small part of the electron bundle emitted by the anode 38 may be segregated by means of an apertured disc or screen 39 whereby a sharp image of the aperture is formed on the fluorescent screen. Electron optical systems for producing and focusing electron images are well known in the art and further details are not thought to be necessary as being outside the scope of the invention.

There is shown in Figure 4 a further improvement and modification of the invention in that the output potentials produced at the output anodes 18 and 19 serve for directly controlling the deflection of the beam of the cathode ray section. For this purpose the anodes 18 and 19 are directly connected to the deflecting plates 43 and 44 respectively as shown. However, it is understood that the electron beam produced by the electrodes 36, 39, 40 and 41 may cooperate with one or more target or output electrodes to obtain a further amplification of the input signals initially applied to the deflecting plates 14 and 15. In this manner, a very compact construction and arrangement is obtained with the shortest possible connections between the associate elements in such a manner that the amplification or recording is substantially independent of the frequency or rate of change of the recording impulses or signals and a sensitivity and amplifying gain is obtained which has heretofore been impossible with arrangements known in the prior art.

As is understood, the invention has many uses in connection with the amplification, modulation or generation of electric as well as in recording of electric current or potential variations. One of these uses is the direct measurement or recording of weak magnetic fields in which case the primary electron beam is controlled by a pair of deflecting coils in place of the deflecting plates 14 and 15 shown in the drawing.

It will be apparent from the above that the invention is not limited to the specific construction and arrangement of parts and circuits shown for illustration, but that the novel thought and underlying idea of the invention is susceptible of numerous variations and modifications coming within the broader scope and spirit of the invention as defined in the appended claims. Accordingly, the drawing and specification should be regarded in an illustrative rather than a limited sense.

I claim:

1. In a discharge device, means for producing a concentrated electron beam, means for deflecting said beam, a pair of foraminous target anodes having high secondary electron emission characteristics and arranged at an angle whose bisecting plane coincides with the axis of said electron beam in its normal position, whereby said target anodes are impinged differentially by gradually varying cross-sectional portions of said electron beam when the latter is deflected in opposite directions between a central and two limit positions in accordance with variations of an applied input signal to be translated, a pair of further anodes arranged at the side of said target

anodes opposite from said electron beam in spaced relation to said target anodes, means for maintaining said further anodes at a positive potential relative to said target anodes, and a push-pull output circuit connected to said further anodes.

2. In a discharge device, means for producing a concentrated electron beam, means for deflecting said beam, an angularly bent foraminous target electrode having high secondary electron emission characteristics and arranged with its bisecting plane coinciding with the axis of said electron beam in its normal position, whereby the angular surfaces of said target electrode are impinged differentially by gradually varying cross-sectional portions of said electron beam when the latter is deflected in opposite directions from its normal position in accordance with variations of an applied input signal to be translated, and a pair of further anodes each disposed in spaced relation to one of the angular surfaces of said target anode and at the side of said target anode opposite from said electron beam, means for maintaining said further anodes at a positive potential relative to said target anode, and an output circuit connected to each of said further anodes.

3. In a discharge device, means for producing a concentrated electron beam, means for deflecting said beam, a pair of foraminous target anodes having high secondary electron emission characteristics and arranged to be impinged differentially by gradually varying cross-sectional portions of said electron beam when the latter is deflected between a central and opposite limit positions in accordance with variations of an applied input signal to be translated, a pair of further anodes each disposed in spaced relation to said target anodes at the side of said target anodes opposite from said electron beam, means for maintaining said further anodes at a positive potential relative to said target anodes, output impedance means connected to each of said further anodes, and at least one further foraminous electrode arranged intermediate said target anodes and said further anodes, each of said intermediate electrodes being capable of high secondary electron emission and biased at a potential positive relative to the potential of the preceding electrode.

4. In a discharge device, means for producing a concentrated electron beam, means for deflecting said beam, a pair of foraminous target anodes, a further foraminous target anode arranged intermediate said first target anodes, whereby said first target anodes are differentially impinged by varying cross-sectional portions of said electron beam when the latter is deflected in accordance with variations of an applied input signal to be translated, said target anodes being conditioned to have high secondary electron emission, and output anodes disposed in spaced relation to each of said target anodes at the side of said target anodes opposite from said electron beam, means for maintaining said output anodes at a positive potential relative to the associated target anodes, and an output impedance connected to each of said output anodes associated with said first mentioned target anodes.

5. In a discharge device, means for producing a concentrated electron beam, means for deflecting said beam, a pair of foraminous target anodes, a further foraminous target anode intermediate said first target anodes, whereby said first target anodes are differentially impinged by varying

cross-sectional portions of said electron beam when the latter is deflected in accordance with variations of an applied input signal to be translated, said target anodes having high secondary electron emission characteristics, output anodes disposed in spaced relation to each of said target anodes, a source of potential for maintaining said output anodes at a positive potential relative to said target anodes, and output impedance means connected between said output anode associated with said first target anodes and said source of potential.

6. In a discharge device, means for producing a concentrated electron beam, means for deflecting said beam, a pair of foraminous target anodes, a further foraminous target anode disposed intermediate said first target anodes, whereby said first target anodes are differentially impinged by varying cross-sectional proportions of said electron beam when the latter is deflected in accordance with variations of an applied input signal to be translated, said target anodes being conditioned to have high secondary electron emission, output anodes disposed in spaced relation to each of said target anodes at the side of said target anodes opposite from said electron beam, means for biasing said output anodes at a positive potential relative to the associated target anodes, output impedance means connected to said further anodes associated with said first mentioned target anodes, the anode associated with said intermediate target anode being of foraminous construction and conditioned to have high secondary electron emission, and means for concentrating and utilizing the electrons emitted by said last mentioned anode in a separate beam within said device.

7. In a discharge device, means for producing a concentrated electron beam, means for deflecting said beam, a pair of foraminous target anodes, a further foraminous target anode disposed in-

termediate said first target anodes whereby said first target anodes are differentially impinged by varying cross-sectional portions of said electron beam when the latter is deflected in accordance with variations of an applied input signal to be translated, said target anodes having high secondary electron emission characteristics, output anodes arranged in spaced relation to each of said target anodes and at the side of said target anodes opposite from said electron beam, means for biasing said output anodes at a positive potential relative to the associated target anodes, output impedance means connected to said further anodes associated with said first mentioned target anodes, the anode associated with said intermediate target anode being of foraminous construction and conditioned to have high secondary electron emission, and means for concentrating and utilizing the electrons emitted by said last mentioned anode in a separate beam within said device.

8. In a device as claimed in claim 7 including means for deflecting said last mentioned electron beam.

9. In a device as claimed in claim 7 including means for deflecting said last mentioned electron beam, and means for directly controlling said last mentioned deflecting means by potential variations developed at said further anodes associated with the first mentioned target anodes.

10. In a device as claimed in claim 6 including means for controlling the electron stream produced by said last mentioned anode and further means for controlling said last mentioned means in accordance with potential variations developed at said further anodes associated with said first mentioned target anodes.

HANS ERICH HOLLMANN.
